UNITED STATES PATENT OFFICE.

ERNEST G. HOWARD, OF SPRINGFIELD, MASSACHUSETTS, ASSIGNOR TO
CHAPMAN VALVE MANUFACTURING COMPANY, OF SPRINGFIELD,
MASSACHUSETTS, A CORPORATION OF MASSACHUSETTS.

MOTOR-DRIVEN VALVE.

SPECIFICATION forming part of Letters Patent No. 777,373, dated December 18, 1904.

Original application filed May 15, 1902, Serial No. 107,457. Divided and this application filed September 18, 1902. Serial No. 123,956. (No model.)

To all whom it may concern:

Be it known that I, ERNEST G. HOWARD, a citizen of the United States of America, residing at Springfield, in the county of Hampden 5 and Commonwealth of Massachusetts, have invented new and useful Improvements in Motor-Driven Valves, (the same being a division of my application filed May 15, 1902, Serial No. 107,457,) of which the following is a specification.

My invention relates to improvements in mechanism for opening and closing the plug or gate of valves, and in particular to electric motors and mechanism for transmitting 15 power therefrom to the plug or gate in which the motor is provided with a hollow armature-shaft through which the valve-spindle extends, said motor being centrally located relative to the longitudinal center of the valve 20 casing or frame; and the objects of my improvement are, first, to secure compactness and space economy in motor-driven valve construction; second, to afford means for locating the motor in a central position in the 25 yoke instead of at one side of the yoke or casing, as formerly; third, to render the transmission of power from a motor so placed effective in every particular; fourth, to provide means for regulating or governing the 30 rotary members, which means can also be used to operate the gate by hand, and, fifth, to provide mechanism which shall render a motor applicable to any of the well-known forms of water, steam, or other valves. I 35 attain these objects by the mechanism illustrated in the accompanying drawings, in which—

Figure 1 is a vertical section of a valve embodying my invention, the motor being partly 40 in elevation; Fig. 2, a plan view of one of the lost-motion devices that I prefer to use, taken on lines α α , Fig. 1; Fig. 3, a perspective view of the spindle-sleeve which forms a part of the aforesaid lost-motion device, and Fig. 4 a side elevation and partial section of the valve complete.

Although certain features of my invention

are applicable to valves without the introduction of lost-motion devices into the mechanism, by employing such devices a much 50 smaller motor can be used, because more power being required to unlock the screw and start the gate, either to raise or lower the same, than is needed for the performance of the subsequent work of opening or closing it 55 it is possible and practicable to supply power necessary for all purposes with a small motor by resorting to one or more of the aforesaid lost-motion devices. By providing a suitable lost-motion device or devices between 60 the motor and gate a small motor is enabled to gather sufficient momentum to overcome the initial resistance.

Valves are divided into two classes—one in which an outside screw is used and another 65 in which an inside screw is used. The present mechanism relates more particularly to the inside-screw construction wherein the spindle is threaded into the gate either directly or indirectly, which moves up or down 70 on said spindle when the same is revolved.

Spur-gears are shown and described; but it will be understood that other mediums for transmitting motion may be used, as worm or bevel gears, chain and sprockets, or any other 75 practical mechanical equivalents.

Similar figures refer to similar parts throughout the several views.

The valve casing or frame comprises a yoke 80 10, mounted on a cap 11, which is in turn mounted on a body 12. A plug or gate 13 is seated in the body 12 and may be raised to the top of the cap 11 by means of a spindle 14, screw-threaded at its lower terminal. The threaded terminal of the spindle 14 may directly engage the threaded sides of a suitable opening or openings provided in the gate 13, or it may engage the threaded sides of an opening in a non-rotary block 15, which has a certain amount of vertical movement in a slot 85 16 in said gate and constitutes one of the means for obtaining lost motion. Any suitable means may be employed to prevent the block 15 from rotating; but simple and effec-

tual means for this purpose are found in a rectangular block having two of its sides in contiguity with opposite sides of the slot 16. Since the block 15 is of less height than the slot 16, it has a certain amount of independent motion irrespective of the gate. The spindle 14 passes through a suitable stuffing-box and follower at the top of the cap 11, and the upper end of said spindle has a sleeve 17 keyed 5 or otherwise attached thereto and adapted to revolve in the yoke-head 18.

An electric motor 19 of any suitable construction having a hollow armature-shaft 20, through which the spindle 14 passes, is fastened 15 between the legs of the yoke 10 by some suitable means, as the bolts 21. The motor, with a hollow armature-shaft, constitutes an essential and valuable feature of my invention. A small gear or pinion 22 is fast on the 20 upper end of the armature-shaft 20 and should be made wholly or in part of some insulating material, as rawhide. The insulating-pinion 22 and insulating-washers 23 23 and bushing 24 around each bolt 21 completely insulate 25 the motor from the surrounding and adjacent parts. A metallic washer 25 may be introduced between each bolt-head and the adjacent washer 23. Power is transmitted from the motor to the spindle by means of an intermediate shaft 26, journaled in an arm 27, projecting forward from the yoke-head 18, fast on the lower end of which is a gear 28, meshing with the pinion 22. Above the gear 28 is a small gear or pinion 29, fast on the 30 shaft 26 and meshing with a gear 30, loose on the spindle 14. A hand-wheel 31 is mounted on the top of the shaft 26 for operating the gate mechanism when the motor is not in use. This hand-wheel may also serve as a balance- 35 wheel for the motor and is very useful in such capacity, since in many, if not most cases, it is necessary to have a regulating or governing medium for the rotary members.

As before stated, the gear 30 is loose on 40 the spindle 14, and it is held against movement longitudinally of said spindle by a flange 32 above and a flange 33 below said gear. The flange 33 may be integral with the spindle or rigidly attached thereto, and the flange 45 32 is preferably integral with the sleeve 17. The spindle-sleeve may revolve freely in the yoke-head 18, but is held against longitudinal movement by the flange 32 below and a collar 34 above said yoke-head, said collar being 50 securely attached to the spindle by means of a set-screw or otherwise. A clutch projection 35 depends from the flange 32 into the path of travel of a clutch projection 36, rising from the gear 30, to provide for lost motion 55 at this point. The clutch projections may be quadrants, as shown, or of other dimensions, provided their combined arcs do not equal a complete circle. Generally, however, the aforesaid clutch projections will not be greater 60 than quadrants, but may be less.

It is obvious that the spindle-clutch projection may be connected with the spindle in any suitable manner other than herein shown and described, or it may be attached directly to said spindle; but the above method is believed to be equal to any, if not the best, from a constructive standpoint. 70

In operation the electric current is turned on to start the motor-shaft 20 and rotate it to the left to open the valve, and the lost motion afforded by the clutch projections is first taken up, then that at the base of the spindle, when the gate is raised. At first the shaft 20 revolves freely outside of the spindle 14 and transmits rotary motion in the same direction to the gear 30 through the medium of the pinion 22 and the intermediate shaft and gears hereinbefore described. The gear 30 makes one-half of a revolution before its clutch projection 36 contacts with the sleeve 80 clutch projection 35, as shown in the drawings, when the sleeve 17 and spindle 14 begin to revolve and the first lost motion is taken up. As the spindle revolves it elevates the block 15 without affecting the gate until said 85 block encounters the top of the slot 16. Then the block as it travels up the spindle raises said gate. The first lost motion allows the motor to gather sufficient momentum to unlock the spindle from the block, and by the 90 time the second lost motion has been taken up there is enough power to start the gate from its seat. The gate continues in its upward course until it encounters the top of the cap 11, when all motion ceases. The valve is now 95 open. To close the valve, reverse the motor to revolve the shaft 20 to the right, and with it the gear 30, which takes up the first lost motion and unlocks the spindle from the block 15. Next said block travels down on 100 said spindle until the second lost motion is taken up by contact with the bottom of the slot 16, when the gate is lowered into the closed position and further movement ceases. During the time that the gate is being raised 105 or lowered the spindle 14 revolves freely in the armature-shaft 20.

It will be readily understood that one of the lost-motion devices may be omitted; but if both were omitted a much larger motor would 110 be required in order to overcome the initial resistance. If the clutch projections are dispensed with, the gear 30 must be fast instead of loose on the spindle 14. By threading the spindle 14 into its gate the other lost motion 115 is eliminated.

Various constructive modifications such as 120 will readily occur to one skilled in the art may be made without departing from the nature of my invention. For example, instead of placing the hand-wheel 31 on the intermediate shaft it may be attached to the top of the spindle 14. In either case the hand-wheel may serve not only as a medium for raising or lowering the gate when for any reason this work cannot be 125

done by the motor, but also as a balance-wheel. If affixed to the intermediate shaft, as in the present construction, the hand-wheel must of course take up both lost motions before the 5 gate is acted upon when this means is resorted to for operating said gate; but if the hand-wheel is affixed directly to the spindle only one lost motion is taken up by it. It will be readily seen, moreover, that the clutch-projection 10 lost-motion device may be introduced into the intermediate shaft mechanism, in which event additional momentum is insured to the motor before the spindle is unlocked from the gate or block. If lost motion is desired at this 15 point, a clutch projection can be added to the gear 28, which would be loose on the shaft 26, and a second clutch projection provided for said shaft. Furthermore, a lost-motion device in the intermediate shaft mechanism, as 20 noted, may be used alone and the device at the spindle omitted. Since a lost-motion device, such as the one just referred to, does not differ in any essential particular from that herein shown and described and specifically 25 illustrated in another application filed by me, I do not deem it necessary to encumber the present application with drawings of the same.

In applications, Serial No. 100,699, filed March 31, 1902, and Serial No. 107,457, filed 30 May 15, 1902, I have shown and described constructions embodying and broadly treating general features of the system herein more specifically treated. The claims of the present application are, however, confined to specific 35 features recited therein, and more particularly the rotary, non-reciprocating valve-stem and the hollow armature-shaft surrounding the same. In another application, Serial No. 123,955, filed simultaneously with this case, 40 certain other features found in this application are specifically claimed, hence are not claimed herein. For these reasons I do not in this application specifically claim the combination, with a motor, of a spindle-driving 45 mechanism between said motor and spindle, comprising rotary members provided with clutch projections extending into each other's paths of travel, a recessed gate, a nut on the spindle in the gate-recess, said nut being 50 of less height than said recess, and means to hold the nut against rotary motion in the recess, as that combination is claimed in said application, Serial No. 100,699; nor do I specifically claim herein in a valve mechanism 55 adapted to be operated both by hand and by power the combination of a valve-casing, a gate arranged therein, a non-reciprocating rotating spindle adapted to operate said gate, a hand-wheel or other equivalent means ar- 60 ranged to turn said spindle, a motor, a train of gearing between the motor and the spindle whereby motion may be communicated from the motor to the spindle, and a lost-motion device in said train comprising a rotating 65 driving part in operative connection with the

motor, a driving member having an abutment to engage the driven member after the driving member has made a part of a revolution, the whole being so arranged that when the motor is at rest the engaging abutments on 70 the lost-motion members are separated from each other, whereby the motor and intermediate driving mechanism start without load and obtain momentum before the driven mechanism is affected and the driven mechanism 75 is started with a sharp blow or impact as contradistinguished from a gradual application of power to the driven mechanism, as this is claimed in said application, Serial No. 123,955. So, too, there is claimed in said application, Serial No. 123,955, the combination, 80 with a valve-casing provided with an external yoke, of a gate or valve within said casing, a rotatable non-reciprocating spindle for actuating said valve, a motor mounted in the yoke 85 and having a tubular armature-shaft which freely encircles the valve-spindle, connecting mechanism located between the motor and yoke-head for indirectly transmitting motion from the motor to the spindle, and one or more 90 lost-motion devices interposed between the motor and the gate, whereby the motor is enabled to acquire momentum before beginning to actuate the gate. For this reason the specific combination just recited is not claimed 95 in the present application.

What I claim as my invention, and desire to secure by Letters Patent, is—

1. In combination with a valve provided with a rotatable non-reciprocating spindle, a 100 motor having a tubular armature-shaft encircling said spindle; intermediate gear connecting the spindle and said tubular shaft; and a member for manually rotating said spindle, adapted also to serve as a balance-wheel when 105 the spindle is rotated by the motor.

2. In combination with a valve-casing provided with a yoke; a wedge-shaped valve within said casing; a rotatable, non-reciprocating valve-spindle for actuating said valve; a motor mounted in the yoke and provided with a tubular armature-shaft which encircles the 110 valve-spindle; and intermediate connections between said tubular shaft and spindle for transmitting motion from the motor to the 115 spindle.

3. In combination with a valve-casing, gate, and non-reciprocating spindle threaded at one end for actuating said gate; a motor having a tubular armature-shaft which encircles but is 120 free from said spindle; indirect connecting mechanism for transmitting motion from the armature-shaft to the spindle; and a member mounted to serve as a balance-wheel for the motor and as a hand-wheel for manually actuating the gate when the motor is out of service.

4. In combination with a valve-casing provided with an external yoke, a gate or valve within said casing; a rotatable, non-recipro- 125

cating spindle for actuating said valve; a motor mounted in the yoke and having a tubular armature-shaft which freely encircles the valve-spindle; connecting mechanism located 5 between the motor and the yoke-head for indirectly transmitting power from the motor to the spindle; and a member for manually rotating the spindle, adapted to serve also as a balance-wheel for the motor when the latter 10 is in operation.

5. In combination with a valve-casing having an external yoke, a gate or valve within said casing; a rotatable, non-reciprocating spindle for actuating said valve; a non-reciprocating 15 sleeve mounted in the yoke-head and fast to the spindle; a motor carried by the yoke and having a tubular armature-shaft which freely encircles the spindle; a gear on said tubular shaft; a gear adapted to operate 20 the sleeve; and intermediate gearing connecting the tubular armature-gear and the sleeve-actuating gear, said gearing being located between the motor and the yoke-head, whereby 25 the motor is enabled to be placed close to the valve-casing.

6. In combination with a valve-casing provided with an external yoke, a gate or valve within said casing; a rotatable, non-reciprocating spindle for actuating said valve; a motor 30 mounted in the yoke and having a tubular armature-shaft which freely encircles the valve-spindle; connecting mechanism located between the motor and the yoke-head for indirectly transmitting motion from the motor 35 to the spindle; and one or more lost-motion devices interposed between the motor and the gate, whereby the motor is enabled to acquire momentum before beginning to actuate the gate.

40 7. In combination with a valve-casing provided with a yoke; a gate or valve within said casing; a rotatable, non-reciprocating spindle for actuating said valve; a motor mounted in the yoke and having a tubular armature-shaft 45 which encircles but is free from the valve-spindle; connecting mechanism located between the yoke-head and the motor for transmitting power from the motor to the spindle; one or more lost-motion devices interposed between the motor and the valve-gate; and a member mounted to serve as a balance-wheel for the motor and as a hand-wheel for manu-

ally actuating said gate when the motor is out of service.

8. In combination with a valve-casing, valve 55 or gate, and rotatable, non-reciprocating spindle for actuating said gate, a motor having a hollow armature-shaft which encircles but is free from said spindle; a gear loose on said spindle; means for transmitting motion from 60 said hollow shaft to said gear; a clutch projection on the gear; and a clutch projection carried by the spindle and extending into the path of the gear clutch projection.

9. In combination with a valve-casing, valve 65 or gate, and rotatable spindle for actuating said gate; a motor having a tubular armature-shaft which encircles but is free from said spindle; a gear loose on said spindle; means for transmitting motion from 70 said tubular shaft to said gear; a clutch projection on the gear; a sleeve fast to the spindle; a clutch projection on the sleeve extending into the path of the gear clutch projection; and means for holding the spindle against longitudinal movement. 75

10. In combination with a valve-casing, a slotted gate; a threaded block in the gate-slot of less height than the slot; a non-reciprocating 80 threaded spindle passing through said block; means to prevent the block from rotating; a motor having a tubular armature-shaft which encircles but is free from the spindle; and means for transmitting motion from the tubular shaft to the spindle. 85

11. In combination with a valve-casing, a slotted gate; a non-rotatable threaded block in the gate-slot of less height than said slot; a threaded spindle passing through said block; a motor having a tubular shaft which encircles but is free from the spindle; a gear loose 90 on said spindle; means for transmitting motion from said tubular shaft to said gear; a sleeve fast to the spindle; a clutch projection on said sleeve extending into the path of the gear clutch projection; and means for holding the spindle against longitudinal movement. 95

In testimony whereof I have signed my name to this specification in the presence of two subscribing witnesses.

ERNEST G. HOWARD.
